PIANO AND LIKE MUSICAL INSTRUMENTS
USING STRINGSPaul H. Bilhuber, Douglaston, N. Y., assignor to
Steinway & Sons, New York, N. Y., a corpora-
tion of New York

Application February 23, 1935, Serial No. 7,887

5 Claims. (Cl. 84—210)

The present invention relates to piano and like musical instruments using strings, and relates more particularly to an improved capo d'astro bar and rib which may be used in the treble section of the string frame and which may be used throughout the string frame to replace the agraffes now universally used.

An object of this improved bar and rib is to limit the speaking length of the strings at the front of the string frame, and to secure a firm, solid connection with the frame so as to prevent energy losses from the vibrating strings.

Another object of the invention is to provide a capo d'astro bar which may be machined to form the rib, and which may be machined more accurately than the usual rib under the capo d'astro bar on the cast iron string frame as the improved bar is straight and is a separate piece bent to shape after machining whereas the usual cast rib is curved and the continuity of the curve is interrupted by the plate bars that cross the capo d'astro bar and rib.

A further object is to provide string clearance for the ends of the strings where they lead to the tuning pins by providing openings in the improved bar which are of suitable size, number or shape through which the strings leading from the rib may freely pass.

The invention also provides a capo d'astro bar and rib which may be welded to a steel plate, the string frame, and which admits of attachment of the improved bar by bolts or screws to a cast iron string frame, and is adaptable to grand piano construction.

Another object is to provide a capo d'astro bar and rib embodying the features of this invention and which may be made in one continuous piece or in separate sections and may be either straight or curved to shape.

With the foregoing and other objects in view, the invention will be more fully described hereinafter, and will be more particularly pointed out in the claims appended hereto.

In the drawing, wherein like symbols refer to like or corresponding parts throughout the several views,—

Figure 1 is a fragmentary end view of a string frame having a capo d'astro bar and rib embodying the features of this invention welded thereto, and adapted to use on a string frame of steel construction.

Figure 2 is an outer edge view of the same, showing one arrangement of the clearance openings for the strings.

Figure 3 is a view similar to Figure 1 but

showing a slight modification in the form of the bar, also welded or otherwise fastened to a string frame of steel construction.

Figures 4 and 5 are like views showing further modified forms wherein the improved bar is bolted to the cast-iron string frame or plate; and

Figure 6 is a fragmentary plan view of a string frame having the improved bar and rib applied thereto.

Referring now to the drawing 20 designates the portion of a spring frame or plate which may be provided with a bearing or bridge 21 over which passes strings 22 extending forwardly to the tuning pins 23, shown in Figure 6.

The improved capo d'astro bar comprises a relatively flat body portion of suitable thickness and of desired length which near one longitudinal edge is overturned on a longitudinal line of bending to the desired extent to provide a shank portion 24 and a beak portion 25. This is preferably a drawn bar. The shank portion 24 is adapted to be secured to the string frame plate 20 at its longitudinal edge by welding, as shown in Figures 1, 2, and 3, or in any other suitable manner 25 to provide a shank which is substantially integral with the plate 20. The shank 24, being seated at its longitudinal edge on the plate, extends at substantially right angles thereto and the beak 25 is disposed at the inner side of the shank 24 30 and extends longitudinally and in spaced relation therefrom so as to engage across a desired number of the strings 22, depending upon the length of the bar. The beak 24 is suitably shaped to provide an inwardly or downwardly facing rib 26 35 for contact with the strings 22 to limit the speaking length of the strings and to take the place of the usual rib of capo d'astro bars, now commonly used and to also take the place, if desired, of the agraffes now generally used throughout 40 the middle and bass sections of string frames.

As the string frame portion 20 is inclined or disposed inwardly of or lower than the string frame pin bearing portion, the capo d'astro bar is so disposed that the rib 26 is disposed inwardly of or below the bridge or bearing 21, so that the strings 22 are deflected or offset so as to hold the major portions of the strings at the desired distance with respect to the piano action while the bridge 21 draws the strings across the 50 under side of the rib 26. To secure the necessary string clearance between the rib 26 and the bearing or bridge 21, the shank 24 of the bar is provided with openings 27 of desired size, number and configuration for accommodating the de- 55

sired number of strings and to admit of the free passage of the strings through the shank 24 without contact therewith. The bar of this invention may be made of steel and in sections of 5 desired length, or may be made in one continuous piece. The steel bars are preferably drawn in the required shape, or machined into final shape, while in straight line condition and are subsequently curved or bent to the desired configuration 10 according to the number of sections and their positions on the string frame.

The mounting for the rib 26 therefor is a rigid and solid one and the bar provides a relatively strong structure for supporting the rib 26. The 15 bar also eliminates the use of the large number of agraffes used on the usual string frame and reduces largely, the number of operations required for assembling a string frame.

As shown in Figure 6, the capo d'astro bar and 20 rib may be provided, at the inner end of the shank 24, with an attaching flange 28 adapted to seat on the upper or lower face of the string frame portion 20, and which may be secured thereto by a desired number of machine screws 25 29, bolts or other suitable fastening devices. This latter construction may be used in string frames where the portion 20 is of cast material used in grand piano construction.

In a string frame without the usual plate bars, 30 which connect in the hitch pin and tuning pin sections of the string frame, the usual capo d'astro bar cannot be employed because there are no plate bars to attach it to. To overcome this difficulty in the barless plate a capo d'astro bar 35 and plate is made in the manner herein described.

My invention has been illustrated and described with some degree of particularity, but it is understood that changes may be made in the 40 form of details and in the construction and arrangement of parts without departing from the spirit and scope of the invention or the scope of the appended claims.

What is claimed is:—

45 1. In combination, a musical instrument frame construction having a horizontal upper surface and an edge portion inclined to the horizontal, a bridge secured to the inclined portion, and a capo d'astro bar secured to said frame and including 50 a shank extending upwardly of the top surface of said inclined portion and at substantially right angles thereto, and a downwardly extending beak

integral with said shank and terminating in a rib disposed below the plane of the horizontal upper surface of the frame, said shank portion having string receiving openings therethrough.

2. In combination, a musical instrument frame 5 construction having a horizontal upper surface and an edge portion inclined to the horizontal, a bridge extending upwardly of the frame, and a capo d'astro bar secured to said inclined edge portion, said bar including a shank fixed to said 10 inclined edge portion and extending upwardly therefrom, a downwardly extending beak carried by said shank, and a rib integral with said beak, said shank portion having string receiving openings therethrough.

3. In combination, a musical instrument frame 15 construction having a horizontal upper surface and an edge portion inclined to the horizontal, a bridge secured to said inclined edge portion and extending upwardly above said horizontal 20 surface, and a substantially U-shaped capo d'astro bar secured to said inclined edge portion outwardly of said bridge and provided with string receiving openings.

4. In combination, a musical instrument frame 25 construction having a horizontal upper surface and an edge portion inclined to the horizontal, a bridge secured to said frame and terminating above said horizontal surface, a capo d'astro bar including a shank having a portion thereof extending above said inclined edge portion and another portion engaging beneath said inclined edge portion, means for securing said latter shank portion to said inclined frame portion, and a rib carried by said shank and offset downwardly 30 from the upper end thereof, said shank being provided with string receiving openings there-through.

5. In combination, a musical instrument frame 40 construction having a horizontal upper surface and an edge portion inclined to the horizontal, a bridge secured to said frame and terminating above said horizontal surface, a capo d'astro bar mounted on said inclined edge portion, and means for securing said bar to said inclined edge 45 portion, said bar comprising a base portion engaging the upper surface of said inclined edge portion, a shank integral with said base and extending upwardly therefrom, and a downwardly offset rib carried by said shank.

50 PAUL H. BILHUBER.
